GAME BOARD FOR USE WITH MARBLES

Karl H. Ruyle, Manitou Springs, Colo.

Application December 6, 1951, Serial No. 17,628

Term of patent 14 years

(Cl. D34—5)

To all whom it may concern:

Be it known that I, Karl H. Ruyle, a citizen of the United States residing at Manitou Springs, in the county of El Paso and State of Colorado, have invented a new, original, and ornamental Design for a Game Board for Use With Marbles of which the following is a specification, reference being had to the accompanying drawing, forming a part thereof.

Fig. 1 is a plan view of a game board for use with marbles, showing my new design.

Fig. 2 is a transverse section of the same as viewed from the indicated line 2—2 at Figure 1.

I claim:

The ornamental design for a game board for use with marbles, as shown.

KARL H. RUYLE.
